(71) Applicant: **Lenovo (Beijing) Co., Ltd.**, Haidian District, Beijing (CN)

Primary Examiner — Angela J Lee

(72) Inventor: **Renjie Wang**, Beijing (CN)

(74) *Attorney, Agent, or Firm* — Brinks Gilson & Lione; G. Peter Nichols

(73) Assignee: **LENOVO (BEIJING) CO., LTD.**, Beijing (CN)

(57) **CLAIM**

(**) Term: **15 Years**

The ornamental design for a display screen or portion thereof with animated graphical user interface, as shown and described.

(21) Appl. No.: **29/542,487**

(22) Filed: **Oct. 14, 2015**

DESCRIPTION

Related U.S. Application Data

(62) Division of application No. 29/445,483, filed on Feb. 12, 2013, now Pat. No. Des. 745,015.

FIG. 1 is the first image in a sequence for a display screen or portion thereof with animated graphical user interface showing my new design;

(30) **Foreign Application Priority Data**

FIG. 2 is the second image thereof;

Dec. 27, 2012 (CN) 2012 3 0656461

FIG. 3 is the third image thereof;

(51) **LOC (10) Cl.** **14-04**

FIG. 4 is the fourth image thereof;

(52) **U.S. Cl.**

FIG. 5 is the fifth image thereof;

USPC **D14/485**

FIG. 6 is another embodiment showing an alternate embodiment of a first image in a sequence for a display screen or portion thereof with animated graphical user interface showing my new design;

(58) **Field of Classification Search**

FIG. 7 is the second image thereof;

USPC D14/485-495; 715/700, 703, 716, 727,

715/730, 771, 773, 778, 779, 780, 784,

715/785, 786, 787, 810, 821, 825, 828,

715/830, 833, 834, 835, 840, 847, 864,

715/973, 974

CPC G06F 3/0482; G06F 8/34; G06F 3/04817;

G06F 3/048

See application file for complete search history.

FIG. 8 is the third image thereof;

FIG. 9 is the fourth image thereof; and,

FIG. 10 is the fifth image thereof.

(56) **References Cited**

The appearance of the animated user interface sequentially transitions between the images shown in FIGS. 1-5 and 6-10.

U.S. PATENT DOCUMENTS

D396,455 S 7/1998 Bier
D461,822 S * 8/2002 Okuley D14/489

The broken line showing the remainder of the display screen or a portion of the display screen in FIGS. 1-10 forms no part of the claimed design.

The subject matter shown in broken lines, for example, the "X's" in FIGS. 1-5 is for illustrative purposes only and forms no part of the claimed design.
